UNITED STATES PATENT OFFICE.

JULES CAHEN, OF PARIS, FRANCE.

DESIGN FOR A BOX OR CASING FOR CIGARETTE-WRAPPERS.

SPECIFICATION forming part of Design No. 24,031, dated February 12, 1895.

Application filed December 28, 1894. Serial No. 533,231. Term of patent 7 years.

To all whom it may concern:

Be it known that I, JULES CAHEN, a citizen of the French Republic, residing at Paris, in the Republic of France, have invented and 5 produced a new and original Design for a Box or Casing for Cigarette-Wrappers, of which the following is a specification.

In the accompanying drawings, which represent a box or casing for cigarette wrappers, 10 embodying my design—Figure 1 is a perspective view of the box or casing, showing the outside of the cover or flap in a partially raised position, with the scroll work displayed thereon in relief; and Fig. 2 is a perspective 15 view showing the longitudinal slot in the box or casing.

The essential features of my design consist of an oblong rectangular box or casing having a longitudinal slot in its upper side or top, 20 along the median line thereof, which extends the full length of the said box or casing; and

having a cover or flap provided with ornamental scroll work in relief, adapted to fold over one side and the top of the box or casing, as shown in the accompanying drawings. 25

In the drawings,—F designates the rectangular box, and E designates the longitudinal slot therein.

C designates the cover for the box, and in Fig. 1 A and B designate ornamental scrolls 30 in relief on the outer side of said cover.

What I claim is—

The design for a box or casing for cigarette 35 wrappers, substantially as herein shown and described.

In testimony whereof I affix my signature in presence of two witnesses.

JULES CAHEN.
